His Attorneys.

UNITED STATES PATENT OFFICE.

JULIUS R. BINDNER, OF ST. LOUIS, MISSOURI.

SHANK FOR TURN SHOES.

Application filed July 11, 1924. Serial No. 725,338.

To all whom it may concern:

Be it known that I, JULIUS R. BINDNER, a citizen of the United States, and a resident of the city of St. Louis and State of Missouri, have invented a new and useful Shank for Turn Shoes, of which the following is a specification.

This invention relates to shanks for turn shoes.

10 An object of the invention is to provide a metallic shank adapted to be secured upon the upper surface of the sole of a shoe with interlocking engagement therewith, whereby longitudinal or lateral displacement of 15 the stiffener is prevented.

Another object of the invention is to provide a novel and efficient means for securing a metallic shank between the sole and the lining of a shoe, so that all of said parts 20 will maintain their proper relationship irrespective of the strains to which the shoe is subjected when worn.

Other objects will appear from the following description, reference being made to 25 the drawing in which—

Fig. 1 is a longitudinal vertical sectional view of the shoe sole having my invention embodied therein.

Fig. 2 is an inverted plan view of the 30 metallic shank.

Fig. 3 is a cross sectional view on the line 3—3 of Fig. 1.

Fig. 4 is a side elevation of a preferred 35 form of the invention.

My improved shank is preferably made of metal or metallic alloy and comprises a plate of a length sufficient to have its rear end resting upon the shoe heel a considerable distance behind the breast wall of the heel 40 and its forward end terminating approximately at the break line of the sole.

I prefer, though I do not limit myself to, a construction in which the rear end of the plate is near the rear wall of the heel and 45 in which the side edges of the heel portion of the plate are near the side edges of the heel and in which the side edges of the plate, intermediate of its ends, have a contour conforming approximately to the contour of the shank of the shoe sole.

In the form of the invention shown the plate comprises a heel portion 1 having a hole 2 therein; a shank portion 3 and a widened front end portion 4 terminating approximately at the break line of the shoe in 50 which the stiffener is placed. An integral

portion 5 of the plate extends rearwardly into the hole 2 toward the rear end thereof, making the hole 2 substantially U-shaped. In side elevation the shank portion 3 is 60 arcuate (Figs. 1 and 4) conforming to the shape of the shank or arch of the shoe in which the shank is placed, so that the shank will function to maintain the arch of the shoe permanently in the desired shape. The 65 device is preferably made of sheet metal and in the use of such material the sheet metal is crimped to provide on its under side and midway between its side edges a longitudinal depending flange 6 of a vertical 70 width less than the thickness of the outer sole of the shoe. The extended portion 5, the shank portion 3 and the front end 4 are formed with tongues 7, of which those on the extension 5 project upwardly and 75 those on the shank portion 3 and the front end 4 project downwardly.

As shown, the shank may be embodied in a shoe by forming a groove in the sole 8 in which the flange 6 is placed, the tongues 7 80 on the shank portion 3 and on the front end 4 being forced into the sole, while the projections 7 on the extension 5 are forced into the member 9 of the shoe. The nails 10 are forced through the member 9, through the 85 hole 2 and downwardly through the heel portion of the sole 8 and into the shoe heel. The hole 2 also provides an opening through which the fastening tacks 11 pass in the preliminary assembling of the parts comprising the sole 8, the metallic shank and the member 9 of the shoe. The member 9 terminates slightly in advance of the breast wall of the shoe heel and forms a smooth 90 support for the lining 12. 95

The construction shown and described prevents relative displacement of the parts, so that the shoe will retain its original shape under the strains and stresses of wear.

I do not restrict myself unessentially, but 100 what I claim and desire to secure by Letters Patent is:—

1. A shoe comprising a sole having a longitudinal groove in the upper side of a portion thereof, a metallic plate having side and end portions of approximately uniform thickness resting upon the top of the sole, a projection rigid with the under side of said plate fitting closely in said groove and terminating short of said end portions of 105 said plate leaving said end portions bearing upon the top of the sole across the ends 110

of said projection, and means for securing said parts in said relationship.

2. A shoe comprising a sole having a longitudinal groove in its upper side for a portion of its length along the shank thereof, a metallic plate having a side and end portions of approximately uniform thickness throughout the length and width thereof resting upon the top of the sole at the sides and beyond the ends of said groove, a projection rigid with said plate fitting closely in said groove throughout the length of said projection, and means for securing said parts in said relationship.

3. A shoe comprising a sole having a longitudinal groove in the upper side of the shank portion thereof, a metallic plate conforming substantially to the shape of the shank portion of the sole, a longitudinal flange extending downwardly from said plate and terminating short of both ends of said plate and fitting closely in said groove leaving the smooth side and end portions of said plate resting upon the sole at the sides and beyond the ends of said groove, and a number of tongues integral with said plate engaging in said sole.

4. A shoe comprising a sole having a longitudinal groove in the upper side of the shank portion thereof, a metallic plate conforming substantially to the shape of the shank portion of the sole, a longitudinal flange extending downwardly from said plate and terminating short of both ends of said plate and fitting closely in said groove

leaving the smooth side and end portions of said plate resting upon the sole at the sides and beyond the ends of said groove, a number of tongues integral with said plate engaging in said sole, a lining supporting portion upon the heel portion of said plate beyond the rear end of said flange, and a lining having its rear portion upon said supporting member and resting directly upon said plate in front of said supporting member.

5. A shank for turn shoes comprising a metallic plate of a length sufficient to extend from a point behind the breast wall of the heel of the shoe for which the shank is intended to a point near the break line of said shoe and having a hole through the rear portion thereof, and a longitudinal depending flange integral with the under side of said plate and terminating between the ends thereof for engagement in a groove in a shoe sole.

6. A shank for turn shoes comprising a metallic plate of a length sufficient to extend from a point behind the breast wall of the heel of the shoe for which the shank is intended to a point near the break line of said shoe and having a hole through the rear portion thereof, a longitudinal depending flange integral with the under side of said plate and terminating between the ends thereof, and means in connection with said plate for engaging a shoe sole at the sides of said flange.

JULIUS R. BINDNER.
